DESIGN FOR A CIGARETTE CONTAINER

Application filed April 4, 1932. Serial No. 43,396. Term of patent 3½ years.

To all whom it may concern:

Be it known that we, MICHELE BERTONCINI, a citizen of the United States, residing at Milwaukee, in the county of Milwaukee, and State of Wisconsin, and WALTER BLATTER, a citizen of the United States, residing at Shorewood, in the county of Milwaukee, and State of Wisconsin, have invented a new, original, and ornamental Design for a Cigarette Container, of which the following is a specification, reference being had to the accompanying drawing forming a part thereof.

The figure is a perspective view of a cigarette container showing our new design.

We claim:

The ornamental design for a cigarette container, substantially as shown.

In witness whereof, we hereunto subscribe our names this 30th day of March, 1932.

MICHELE BERTONCINI.
WALTER BLATTER.
